UNITED STATES PATENT OFFICE.

THOMAS J. LOFTUS, OF CASTELLA, CALIFORNIA, ASSIGNOR OF ONE-HALF TO HARMON BELL, OF OAKLAND, CALIFORNIA.

ROTARY ENGINE.

1,276,381.

Specification of Letters Patent. Patented Aug. 20, 1918.

Application filed October 16, 1917. Serial No. 196,819.

To all whom it may concern:

Be it known that I, THOMAS J. LOFTUS, a citizen of the United States, residing at Castella, in the county of Shasta and State 5 of California, have invented new and useful Improvements in Rotary Engines, of which the following is a specification.

This invention relates to a rotary engine of the internal combustion, multi-cylinder 10 type, and particularly to improvements over the structure shown in my co-pending application entitled "rotary engine," filed August 15th, 1917, Serial Number 186,306.

One of the objects of the present invention is to provide a rotary cylinder, internal combustion engine operating on the four-cycle principle, in which the crank case and cylinder are mounted eccentrically with relation to the crank shaft and in which both 20 the cylinders and crank shaft revolve. Another object of the invention is to provide a crank shaft to which two revolutions are imparted while the cylinders make one revolution; and also to provide a novel cam arrangement whereby two reciprocations are 25 imparted to the pistons during one revolution of the cylinders to permit a perfect charging and scavenging of the cylinders. Further objects will hereinafter appear.

30 The invention consists of the parts and the construction and combination of parts as hereinafter more fully described, and claimed, having reference to the accompanying drawings, in which—

35 Figure 1 is a central, vertical, longitudinal section through the engine.

Fig. 2 is a central, vertical, cross section.

Fig. 3 is a front view of the cam head, showing the position of the inlet valve cam.

40 Fig. 4 is a front view of the cam head which carries the exhaust valve cam.

Fig. 5 is another view of one of the cam heads, showing a modification in the construction of same.

45 Referring to the drawings in detail, A and B indicate a pair of bearing members, in which are journaled, respectively, a crank shaft 2 and a cylinder shaft 3. Suitably secured or formed integral with the cylinder

50 shaft is a crank casing 4, and radially positioned with relation to the cylinder shaft and secured to the crank case in any suitable manner is a plurality of cylinders 5. The cylinders provided are preferably ribbed, as

55 shown at 6, to permit air cooling, and T-heads are employed for the reception of an

exhaust valve 7 and an inlet valve 8, the valves employed being of the puppet type.

Each valve is provided with a stem 9 surrounded by a spring 10 which engages a 60 collar 11, thereby providing a means for normally retaining each valve on its seat. The lower end of each stem is projected through a flange 12 formed on each side of the cylinder near the inner end, and both 65 valve stems are positioned in direct alignment with a pair of cam heads, generally indicated at 13 and 14. These cam heads are stationary, one being secured by a set-screw 15, or any other suitable means, on the inner end of the bearing A, while the opposite cam head 14 is secured on the inner end of a stationary hollow shaft 16 secured in the bearing B. The cylinder shaft is journaled both in the bearing B and on the stationary 70 shaft 16. The cylinder shaft may, therefore, be termed a sleeve shaft having both an interior and an exterior support. One side of the crank case supporting the cylinders is provided with a number of cored passages 75 17, one for each cylinder and inlet valve 8.

The inner ends of these cored passages communicate with perforations formed in the sleeve shaft and also in the hollow stationary shaft 16, while the outer ends are 80 connected through pipes 18 with the intake ports formed in the cylinders. The hollow stationary shaft may, therefore, be directly connected with a carburetor of any suitable construction and the gas admitted will thus 85 travel through the stationary, hollow shaft and the perforations formed therein, thence through the cored passages and pipes 18 directly to each inlet valve, the admission of gas being controlled by opening and closing 90 the inlet valves by means of a cam 19 formed on the outer periphery of the stationary cam head 14; that is, the inner ends of the stems carrying the valves 8 are so positioned that they will engage the cam 19 once during 95 each revolution of the cylinders, thus providing a means for lifting each inlet valve once during each revolution of the cylinders. The exhaust valves are also opened once during each revolution of the cylinders by 100 means of a cam 20 formed on the outer periphery of the stationary cam head 13.

Slidably mounted in each cylinder is a piston 21, and formed as an integral part of each piston is a rigid connecting rod 22, 110 on the lower end of which is formed a half journal section 23. These journal sections

are separated, as shown at 24, to permit the connecting arms to straddle the crank arms 25 carried by the crank shaft and also to permit a perfect engagement, as will hereinafter be described, with a double crank pin 26 carried by each crank. One side of each journal member 23 is provided with a pin extension 27 which supports a roller 28, said rollers being so positioned that they will always run in engagement with a pair of circular cam grooves 29 and 30 formed in each cam head 13 and 14.

The crank shaft, as previously stated, is eccentrically positioned with relation to the crank case and the cylinders. The crank arms and pins 26 carried thereby are, furthermore, so short that a positive connection between the rigid piston connecting rods and the pins cannot be obtained. It may, furthermore, be stated that such engagement is neither desired nor intended, as one of the objects of the present invention is to permit two reciprocations of each piston and two complete revolutions of the crank shaft to each revolution of the cylinders, the two reciprocations of the pistons during one revolution of the cylinders permitting a four-cycle operation and simultaneously reduces the cylinder speed to one-half of that which is required in ordinary standard four-cycle revolving cylinder engines. The centrifugal strains to which such cylinders are subjected are entirely overcome by the present structure, as the comparatively slow speed of the cylinders with relation to the crank shaft permits a high propeller speed and a low cylinder speed. Lighter material and a more compact construction and assembly are also permitted in the present instance; and the efficiency is rather higher, due to the longer opening period of both the intake and exhaust valves.

The operation of the engine will be as follows: Referring to Figs. 2, 3 and 4, the sweep of the crank pins 26 conforms to or travels in exact alignment with the lower half 30 of the cam grooves formed in the heads 13 and 14. The movement of the pistons is not only positively timed and regulated by the grooves 29 and 30 but also by the revolution of the crank shaft. To illustrate the movement of the pistons during one revolution, we might commence with the suction stroke of a single piston. In that instance, commencing with the piston shown in cylinder 5^a, which is in alignment with the intake cam 19, it might be stated that the inlet valve remains open during the travel of the cylinder from the point indicated at 31 to the point 32. The piston travels inwardly during this movement of the cylinder, due to the engagement of the rollers 28 with the upper half of the cam groove 29, a complete inward movement of

the piston being obtained when the cylinder reaches the point 32. The piston will similarly travel outward until the point 33 is reached, thus fully compressing the charge admitted. This outward movement is due not only to the shape of the lower half of the cam grooves 30, but also to the fact that the connecting rod bearings 23 are engaged by the crank pins 26, thereby forcing the piston outwardly during the revolution of the cylinders from the point 32 to the point 33.

Ignition takes place in a position preferably ahead of the point 33 and burning of the gases will, therefore, force the piston inwardly against the crank pins, thereby imparting the power stroke; a complete expansion or burning of the gases having taken place when the cylinder reaches the point 34. The exhaust cam, carried by the head 13, is engaged at this point and the valve remains open while the cylinder travels from the position shown at 34 to the point 31 and outward movement of the piston being insured by the shape of the upper half of the cam grooves 29.

One reciprocation of each piston takes place while the pistons travel in engagement with their crank shaft pins and the second reciprocation of each piston takes place during the other half of the revolution of the cylinders or when the pistons travel free of the crank pins but in engagement with the upper halves 29 of the cam grooves. Engagement of a piston with a crank shaft pin takes place during one whole revolution of the crank shaft and during one half of a revolution of the cylinders, that is, a crank pin engages a piston connecting rod at the point 32, shown in Figs. 2 and 3, and does not leave the connecting rod until the point 34 is reached. Two revolutions are transmitted to the crank shaft during one revolution of the cylinders and two reciprocations are also transmitted to each piston during one revolution of the cylinders, thereby permitting a four-cycle operation and a complete charging and scavenging of each cylinder due to the long opening period permitted by the position of the cams 19 and 20.

While any suitable form of ignition system may be employed, an adjustable wipe contact member 36 carried by the bearing A is shown. This wipe member engages the lower terminal ends 37 of the wires connected with the respective plugs. Adjusting of the stationary member 26 permits advancing or retarding of the spark in the usual manner.

Any suitable source of current supply may be employed, such as a high tension magneto or the like, and a running fit may be formed between the stationary cam heads 13 and 14 and the revolving crank case to permit a lubricant to be admitted through

a pipe 40, the running fit preventing any unnecessary leakage around the stationary cam heads and the revolving cylinders. I also wish it understood that the materials 5 and finish employed in general may be such as the experience and judgment of the manufacturer may dictate.

The construction of the crank shaft and pistons here provided is identical to that 10 shown in my co-pending application, but the feature which forms the important part of the present application is the provision of double cam grooves 29 and 30 and mechanically operated valves for the admission 15 and scavenging of the charges, the specific construction and manner of introducing the charges being immaterial as it is obvious that any suitable arrangement may be provided.

20 By referring to Fig. 5, it will be seen that the upper cam section 29^a is larger than those illustrated in Figs. 3 and 4. This is of great importance particularly where an engine of the type described is 25 employed for aviation purposes. That is, the large cam 29^a provided increases the stroke of the piston during the scavenging and suction charge. Increased stroke causes the piston to enter what is normally termed 30 the compression space, thereby serving as a means for completely scavenging the gases on the exhaust stroke and also serving as a means for increasing the volumetric charge of the cylinder during the suction stroke.

35 The importance of this can readily be appreciated when it is taken into consideration that aviation engines often travel at such heights that the atmospheric pressure is so reduced that comparatively low 40 compression is obtained during the compression strokes of the pistons. Any increase in volumetric capacity under such conditions is therefore a vital factor in the successful operation of an engine of this type.

45 Another feature obtained is an increase in length of both the exhaust and inlet cams which further facilitates a more complete scavenging and charging of the cylinders.

Having thus described my invention, what 50 I claim and desire to secure by Letters Patent is—

1. A four-cycle rotary internal combustion engine comprising a plurality of revolving cylinders, a revolving crank shaft 55 eccentrically positioned with relation to the cylinders, a piston in each cylinder, means for transmitting piston movement to revolve the crank shaft and means for transmitting two reciprocations to each piston during one revolution of the cylinders, said means also adapted to increase the length of the piston stroke during one-half revolution of the cylinders and decrease the length during the other half of the revolution of the cylinders.
2. A four-cycle rotary internal combus-

tion engine comprising a plurality of revolving cylinders, a piston in each cylinder, a rigid connecting rod in each piston, a bearing member on the lower end of each connecting rod, a revolving crank shaft eccentrically positioned with relation to the cylinders, crank pins on said shaft, means causing the rigid connecting rod bearings to engage the crank pins during one-half revolution of the cylinders and to transmit two 70 revolutions to the crank shaft during one revolution of the cylinders and means for transmitting two reciprocations to each piston during one revolution of the cylinders. 75

3. A four-cycle rotary internal combustion engine comprising a plurality of revolving cylinders, a piston in each cylinder, a rigid connecting rod in each piston, a bearing member on the lower end of each connecting rod, a revolving crank shaft eccentrically positioned with relation to the cylinders, crank pins on said shaft, means causing the rigid connecting rod bearings to engage the crank pins during one-half revolution of the cylinders and to transmit two 80 revolutions to the crank shaft during one revolution of the cylinders and a pair of stationary cam members controlling the reciprocal movement of each piston, said cam members adapted to lengthen the piston 85 stroke during the exhaust and charging cycle and to decrease the stroke during the compressing and firing cycle. 90

4. A four-cycle rotary internal combustion engine comprising a plurality of revolving cylinders, a piston in each cylinder, a rigid connecting rod in each piston, a bearing member on the lower end of each connecting rod, a revolving crank shaft eccentrically positioned with relation to the cylinders, crank pins on said shaft, means causing the rigid connecting rod bearings to engage the crank pins during one-half revolution of the cylinders and to transmit two 100 revolutions to the crank shaft during one revolution of the cylinders, a pair of stationary cam members controlling the reciprocal movement of each piston, said cam members adapted to lengthen the piston 105 stroke during the exhaust and charging cycle and to decrease the stroke during the compressing and firing cycle. 110

5. A rotary cylinder engine comprising a crank case, a plurality of radially disposed cylinders secured to the crank case, a cylinder shaft journaled to rotate carrying the crank case and cylinders, a crank shaft journaled to rotate independently of the cylinder shaft and positioned eccentrically thereto, a piston in each cylinder, a rigid 125

1. connecting rod on each piston, a stationary cam head at each end of the crank case, each head having two connected circular superposed grooves formed on their inner sides, 5 a bearing member on the inner end of each connecting rod, a projecting pin on each end of each bearing member adapted to be received by the circular grooves formed in the cam heads, a plurality of radially disposed arms on the crank shaft between the cam heads, and a pin on the outer end of each arm adapted to be engaged by the connecting rod bearing members during one-half of a revolution of the cylinders.
- 15 6. A rotary cylinder engine comprising a crank case, a plurality of radially disposed cylinders secured to the crank case, a cylinder shaft journaled to rotate carrying the crank case and cylinders, a crank shaft 20 journaled to rotate independently of the cylinder shaft and positioned eccentrically thereto, a piston in each cylinder, a rigid connecting rod on each piston, a stationary cam head at each end of the crank case, each head having two connected circular superposed grooves formed on their inner sides, one of said circular grooves being larger in diameter than the other, a projection on each side of each connecting rod adapted to 25 be received by the grooves, a bearing member on the lower end of each connecting rod, crank pins on the crank shaft adapted to be engaged by the connecting rod bearings during a portion of the revolution of the 30 cylinders, an exhaust and an inlet valve in each cylinder, and a cam member in each cam head adapted to alternately open said valves once during each revolution of the cylinders.
- 35 7. A rotary cylinder engine comprising a crank case, a plurality of radially disposed cylinders secured to the crank case, a cylinder shaft journaled to rotate carrying the crank case and cylinders, a crank shaft 40 journaled to rotate independently of the cylinder shaft and positioned eccentrically thereto, a piston in each cylinder, a rigid connecting rod on each piston, a stationary cam head at each end of the crank 45 case, each head having two connected circular superposed grooves formed on their inner sides, a bearing member on the inner end of each connecting rod, a projecting pin on each end of each bearing 50 member adapted to be received by the circular grooves formed in the cam heads, a plurality of radially disposed arms on the crank shaft between the cam heads, a pin on the outer end of each arm adapted to be 55 engaged by the connecting rod bearing members during one-half of a revolution of the cylinder, an exhaust and an inlet valve 60
- in each cylinder, and a cam member in each cam head adapted to alternately open said valves once during each revolution of the cylinders. 65
8. A four-cycle rotary internal combustion engine comprising a plurality of revolving cylinders, a revolving crank shaft, means for transmitting power to turn the crank shaft two revolutions during one revolution of the cylinders, a piston in each cylinder, means for transmitting two reciprocations to each piston during one revolution of the cylinders, and means for increasing the length of the piston stroke during one-half of a revolution of the cylinders and decreasing the length during the other half of revolution of the cylinders. 70
9. A four-cycle rotary internal combustion engine comprising a plurality of revolving cylinders, a revolving crank shaft, means for transmitting power to turn the crank shaft two revolutions during one revolution of the cylinders, a piston in each cylinder, means for transmitting two reciprocations to each piston during one revolution of the cylinders, means for increasing the length of the piston stroke during one-half of a revolution of the cylinders and 75 decreasing the length during the other half of revolution of the cylinders, said means comprising a circular cam groove regulating the stroke of the piston during the compression and firing cycles and a connected larger circular cam groove which controls the stroke of the piston during the exhaust and charging cycle. 80
10. A four-cycle rotary internal combustion engine comprising a plurality of revolving cylinders, a revolving crank shaft, means for transmitting power to turn the crank shaft, a piston in each cylinder, means for transmitting two reciprocations to each piston during one revolution of the cylinders, means for increasing the length of the piston stroke during one-half of a revolution of the cylinders and decreasing the length during the other half of the revolution of the cylinders, said means comprising a circular cam groove regulating the stroke of the pistons during the compression and firing cycles and a connected larger circular cam groove which controls the stroke of the pistons during the exhaust and 85 charging cycle. 90
